UNITED STATES PATENT OFFICE.

LOUIS MARX, OF BROOKLYN, NEW YORK.

ROUNDABOUT TOY.

Application filed July 19, 1926. Serial No. 123,288.

This invention relates to a toy or amusement device and more particularly to a mechanically operated toy; and has special reference to the provision of an improved 5 roundabout toy or amusement device.

One of the principal objects of my present invention comprehends the provision of an improved roundabout toy or amusement device in which a figure such as a vehicle or the like is caused to rotate about a platform with means provided operable by the rotation of the vehicle for causing another figure simulating a traffic officer to move into a position adjacent the path of movement of the vehicle 15 to indicate or signal the said vehicle to stop. A further and ancillary object of the invention comprehends the provision of a roundabout toy of this character in which means are provided for automatically bringing the vehicle to a stop or halt when the traffic officer figure moves into stop or halt signalling position.

A further prime object of the invention comprehends the provision of an improved 25 roundabout toy of the character referred to in which the means for automatically stopping the rotation of the vehicle and the means for actuating the movable traffic officer figure are operated only after the vehicle 30 has moved uninterruptedly a plurality of cycles or revolutions about the platform so that the toy may be set to permit unhindered rotation of the vehicle for a plurality of revolutions or cycles.

A still further prime object of the invention resides in the provision of an improved roundabout toy embodying an automatic 35 stop mechanism for the rotatable vehicle combined with a figure simulating a traffic officer acting in the performance of his duties in which all the parts are operated by a single motor mechanism, the said parts being constructed and inter-related to permit of the manufacture of the toy with a minimum of operated parts and the durable use thereof with efficiency.

To the accomplishment of the foregoing and such other objects as will hereinafter appear, my invention consists in the elements 50 and their relation one to the other, as herein-after more particularly described and sought to be defined in the claims; reference being had to the accompanying drawings which show the preferred embodiment of my invention, and in which:

Fig. 1 is a perspective view of a round-

about toy embodying the principles of my present invention,

Fig. 2 is a fragmentary and enlarged bottom plan view thereof, 60

Fig. 3 is a view thereof taken in cross-section on the line 3—3, Fig. 1, and

Fig. 4 is a fragmentary cross-sectional view of a detail thereof.

Referring now more in detail to the drawings, the toy or roundabout device of my invention comprises in its general aspects a platform or support generally designated as A, the movable figure B movable cyclically around the platform A and operated by a 65 motor generally designated by the motor housing C on the platform A, the cyclic rotation of the figure B being controlled by an automatic stop mechanism operating in conjunction with the movement of a figure simulating a traffic officer, all generally designated as D.

The platform or support A is preferably of the type in which an annular track is provided for the movement of the movable 80 figure, and said platform comprises a central disk section 10, an annular section 11, the said annular section being spaced from the central disk section 10 so as to provide or define an annular track 12 in which the 85 figure B moves. The annular section 11 is provided with a depending skirt portion 13 which forms a support for the toy and the disk section 10 is supported on the annular section 11 by means of a plurality of arches 90 14, 14 (three in number) which may be given any desired contour or design. The disk section 10 supports the operating and operated parts of the toy, as will be seen more in detail hereinafter.

The movable figure B may be made to simulate a figure or animal, and in the construction exemplified in the drawings the figure is shown in the form of an automotive vehicle which in its simplest form may be made of 100 suitably embellished sheet material cut and bent into the desired configuration.

The vehicle figure B is cyclically rotated in the annular track 12 by means of the motor which is supported on the disk section 105 10 of the platform, which motor (not shown) is housed in the motor casing C through which projects a winding key 15 adapted to be grasped for winding the motor, the said motor including a driven shaft 16 which extends to the underneath of the disk section 110 10 of the platform and which is preferably

integral with a radially extending connecting rod 17 which is provided at its front end with an upwardly bent portion 18 fixed to the vehicle B. From this construction it 5 will be apparent that when the motor is energized by the winding key 15, the operating shaft 16 thereof will be actuated to move the vehicle B cyclically in its track.

The automatic stop mechanism D in the 10 present form of my invention comprises means which is movable transversely of the platform into the path of movement of the rotatable figure to automatically stop the rotation of said figure; and in the preferred 15 construction said means includes mechanism operable only after the figure has moved uninterruptedly a plurality of cycles or revolutions about said platform. In the preferred construction this means comprises a spring- 20 actuated member 19 slidably movable on a rod 20 arranged underneath the platform 10 between the full and dotted line positions shown in Fig. 2 of the drawings, which rod is anchored to the platform at points 21 and 25 22 thereon. The member 19 is normally held in the full-line position by means of a latch 23 pivoted at 24 on the platform 10, the said latch being held in its normal latching 30 position as shown in full lines in Fig. 2 of the drawings by means of the leaf spring 25 anchored at 26 to the underneath side of the platform, the said latch being movable by means hereinafter to be described into the dotted-line position shown in Fig. 2 to release 35 the slidable member 19, which latter is actuated by means of the compressed spring 27 which encircles the supporting rod 20. When the latch 23 is operated to the unlatching position, the member 19 will be 40 spring-projected into the dotted line position and into the path of movement of the vehicle driving rod 17, bringing the vehicle B to a halt.

Combined with the automatic stop mechanism for the vehicle, I provide a figure movable above the platform 10, the said figure simulating a motorcycle traffic officer, which figure is made preferably integral with the automatic stop mechanism so that both are 45 simultaneously operated when the latch is released. This traffic officer figure comprises the wheeled member 28 movable from a concealed position behind the motor casing C as shown in full lines in Figs. 1 and 3 to a position adjacent the vehicle B as shown in dotted lines in Fig. 1 of the drawings, the latter position being the stop indicating 50 position. By reference to Fig. 1 it will be noted that the figure in the stop indicating position simulates the signalling to the vehicle B to bring the latter to a stop or halt, the same being stopped by the simultaneous 55 operation of the stop member 19. The figure 28 made of any suitable sheet material 60 is integral with the parts 19a of the stop

member 19, which parts project through an elongated slot 29 arranged in and transversely of the platform disk 10, the said slot defining the locus of movement of the traffic officer 28.

In the preferred construction, as aforesaid, the automatic stop mechanism and the traffic officer figure are operated only after the rotatable figure has moved a plurality of cycles or revolutions, and this is accomplished by the provision of a rotatable element 30 having a predetermined number, such as five, pins 31, 31 thereon which project in the path of movement of a finger 32 fixed to the connecting rod 17, the construction being such that during each revolution of the vehicle and the rod 17, a pin 31 is engaged by the finger 32 to move the rotatable element 30 a part such as a fifth of a turn in the direction shown by the arrow 55 in Fig. 2 of the drawings. The rotatable element 30 is provided with a latch releasing finger 33 which partakes of the movement of the rotatable element 30 and which is therefore brought into a position to pass 60 and engage the terminal finger 34 of the latch 23 after the element 30 has made a complete revolution, this being effected after the vehicle B has made five revolutions. When the latch 23 is thus engaged, 65 the same is moved to the dotted-line position, effecting the release of the elements of the stop mechanism D which brings the vehicle to a halt and causes the traffic officer figure 28 to be projected into the stop indicating 70 position. Preferably to produce a braking action on the rotatable element 30 the same is provided with a spring washer 35 interposed between the element 30 and the platform disk 10, as clearly shown in 75 Figs. 3 and 4 of the drawings.

By means of this construction, therefore, it will be seen that after the rotatable vehicle B has moved a plurality of cycles, the mechanism D normally held in retracted position is released by the operation of the vehicle B to bring the vehicle to a halt and to move the traffic officer figure 28 from a concealed position to a halt indicating position. To release the parts in order to permit continued activity of the toy for another plurality of cycles until the operating motor is unwound, it is only necessary to manually move the motorcycle figure 28 back to the full-line position shown in Fig. 1 and by so doing, the spring operated latch 23 returns to the full-line position shown in Fig. 2, latching the parts in their normal or retracted positions. The rotatable element 30 is at such time in a position to permit the continued operation or rotation of the vehicle B.

The use and operation of my roundabout toy and the many advantages thereof will 130 in the main be apparent from the above de-

tailed description thereof. It will be further apparent that while I have shown and described my invention in the preferred form, that many changes and modifications 5 may be made in the structure disclosed without departing from the spirit of my invention, defined in the following claims.

I claim:

1. In an amusement device, a platform, a 10 motor on said platform, a figure rotatable cyclically around said platform and connected to and operated by said motor, and an automatic stop mechanism for the rotatable figure, said stop mechanism comprising 15 means movable transversely of said platform into the path of movement of the rotatable figure to automatically stop the rotation of said figure, said means including mechanism operable after the figure has 20 moved uninterruptedly a plurality of cycles or revolutions about said platform.

2. In an amusement device, a platform, a 25 motor on said platform, a figure rotatable cyclically around said platform and connected to and operated by said motor, and an automatic stop mechanism for the rotatable figure, said stop mechanism comprising 30 means movable transversely of said platform into the path of movement of the rotatable figure to automatically stop the rotation of said figure, said means including mechanism operable by the movement of said figure after the figure has moved uninterruptedly 35 a plurality of cycles or revolutions about said platform.

3. In an amusement device, a platform, a 40 motor on said platform, a figure rotatable cyclically around said platform and connected to and operated by said motor, and an automatic stop mechanism for the rotatable figure, said stop mechanism comprising 45 means normally held in a retracted position and movable transversely of said platform into the path of movement of the rotatable figure to automatically stop the rotation of said figure, and mechanism operated by the movement of the figure for releasing the stop mechanism.

4. In an amusement device, a platform, a 50 motor on said platform, a figure rotatable cyclically around said platform and connected to and operated by said motor, a second figure on said platform normally held in a retracted position and movable 55 transversely of said platform into a position adjacent the path of movement of said rotatable figure, mechanism for stopping the movement of said rotatable figure and means operable for releasing said second figure to 60 permit the same to move into cooperation with said rotatable figure and for simultaneously actuating the stop mechanism to stop the rotation of the rotatable figure.

5. In an amusement device, a platform, a 65 motor on said platform, a vehicle figure ro-

tatable cyclically around said platform and connected to and operated by said motor, a second figure simulating a motorcycle traffic officer on said platform normally held in a retracted position and projectable transversely of said platform into a stop indicating position adjacent the path of movement of said vehicle figure, mechanism for stopping the movement of said vehicle figure and means operable for releasing said second figure to permit the same to move into its stop indicating position and for simultaneously actuating the stop mechanism to stop the rotation of the vehicle figure. 75

6. In an amusement device, a platform, a 80 motor on said platform, a figure rotatable cyclically around said platform and connected to and operated by said motor, a second figure on said platform normally held in a retracted position and movable transversely of said platform into a position adjacent the path of movement of said rotatable figure, mechanism for stopping the movement of said rotatable figure and means operable after the rotatable figure has moved 85 uninterruptedly a plurality of cycles about said platform for releasing said second figure to permit the same to move into cooperation with said rotatable figure and for simultaneously actuating the stop mechanism 90 to stop the rotation of the rotatable figure. 95

7. In an amusement device, a platform, a motor on said platform, a figure rotatable cyclically around said platform and connected to and operated by said motor, a 100 second figure movable transversely on said platform, spring actuated means for operating said second figure normally held in a retracted position, mechanism for stopping the movement of said rotatable figure and means operable by the movement of the rotatable figure to release the spring actuated means to permit the second figure to move into cooperation with said rotatable figure and for simultaneously actuating the stop mechanism 105 to stop the rotation of the rotatable figure. 110

8. In an amusement device, a platform, a motor on said platform, a figure rotatable cyclically around said platform and connected to and operated by said motor, a second figure movable transversely on said platform, spring actuated means for operating said second figure, a latch for normally holding the spring actuated means in a retracted position, mechanism integral with the spring actuated means for stopping the movement of said rotatable figure and means operable to release said latch to permit the second figure to move into cooperation with said rotatable figure and to permit operation 120 of the stop mechanism. 125

9. In an amusement device, a platform, a motor on said platform, a figure rotatable cyclically around said platform and con- 130

5 nected to and operated by said motor, a second figure movable transversely on said platform, spring actuated means for operating said second figure, a latch for normally holding the spring actuated means in a retracted 10 position, mechanism integral with the spring actuated means for stopping the movement of said rotatable figure and means operable to release said latch to permit the second figure to move into cooperation with said rotatable figure and to permit operation of the stop mechanism, said latch releasing means including instrumentalities operable by the movement of the rotatable figure after 15 the same has moved unhindered a plurality of cycles about said platform.

10. In a device of the class described, a vehicle movable in a predetermined path, a motor operating said vehicle, a figure normally held in a retracted position and movable into a position adjacent the path of movement of said vehicle, mechanism for stopping the movement of said vehicle and means operable for releasing said figure and 25 causing the same to move into cooperation with said vehicle and for simultaneously actuating the stop mechanism to stop the movement of said vehicle.

11. In a device of the class described, a vehicle movable in a predetermined path, a motor operating said vehicle, a simulated motorcycle traffic officer figure normally held in a concealed retracted position and movable transversely into a position adjacent the path of movement of said vehicle, spring actuated means for operating the figure, mechanism for stopping the movement of said vehicle and means operable for releasing said figure and causing the same to be 40 projected by the spring actuated means into cooperation with said vehicle and for simultaneously actuating the stop mechanism to stop the movement of said vehicle.

12. In a device of the class described, a support, a vehicle movable in a predetermined path relative to the support, a motor operating said vehicle, a wheeled figure above said support normally held in a re-

tracted position thereon and movable into a position adjacent the path of movement of said vehicle, mechanism below said support movable into the path of movement of the vehicle for stopping the movement of said vehicle and means operable by the movement of the vehicle for releasing said figure and causing the same to move into cooperation with said vehicle and for simultaneously actuating the stop mechanism to stop the movement of said vehicle.

13. In a device of the class described, a platform, a vehicle movable in a predetermined circular path, a motor operating said vehicle, a wheeled figure movable above said platform from a retracted position into a position adjacent the path of movement of said vehicle, spring actuated means for operating the wheeled figure, a latch for said spring actuated means, mechanism integral with said means for stopping the movement of said vehicle and means operable by the vehicle for releasing said latch and causing the wheeled figure to move into cooperation with said vehicle and causing the stop mechanism to stop the movement of said vehicle.

14. In a device of the class described, a platform, a vehicle movable in a predetermined circular path, a motor operating said vehicle, a wheeled figure movable above said platform from a retracted position into a position adjacent the path of movement of said vehicle, spring actuated means for operating the wheeled figure, a latch for said spring actuated means, mechanism integral with said means for stopping the movement of said vehicle, means operable for releasing said latch and causing the figure to move into cooperation with said vehicle and causing the stop mechanism to stop the movement of said vehicle, and means operated by the vehicle after the same has made a plurality of revolutions for operating the latch releasing means.

Signed at New York city in the county of New York and State of New York this 15th day of July, A. D. 1926.

LOUIS MARX.
